UNITED STATES PATENT OFFICE

165,541

BROOCH OR SIMILAR ARTICLE

Alfred Philippe, Scarsdale, N. Y., assignor to Trifari, Krussman & Fishel, Inc., New York, N. Y.

Application July 9, 1951, Serial No. 15,802

Term of patent 7 years

(Cl. D45—19)

To all whom it may concern:

Be it known that I, Alfred Philippe, a citizen of the United States of America, residing in Scarsdale, county of Westchester, and State of New York, have invented a new, original, and ornamental Design for a Brooch or Similar Article, of which the following is a specification, reference being had to the accompanying drawing, forming part thereof.

Fig. 1 is a plan view of a brooch or similar article showing my new design.

Fig. 2 is an edge view thereof.

Fig. 3 is a plan view illustrating the brooch in open position.

I claim:

The ornamental design for a brooch or similar article, substantially as shown.

ALFRED PHILIPPE.
